UNITED STATES PATENT OFFICE.

CLINTON J. WARREN, OF WINCHESTER, MASSACHUSETTS.

AUTOMOBILE-HANDLING DEVICE FOR GARAGES AND THE LIKE.

1,392,610.

Specification of Letters Patent.

Patented Oct. 4, 1921.

Application filed February 19, 1919. Serial No. 278,094.

To all whom it may concern:

Be it known that I, CLINTON J. WARREN, a citizen of the United States, residing at Winchester, in the county of Middlesex and State of Massachusetts, have invented certain new and useful Improvements in Automobile-Handling Devices for Garages and the like, of which the following is a specification.

10 This invention relates to improvements in automobile handling devices for garages and the like. More particularly it relates to means for getting automobiles quickly and conveniently to and from the upper floors of a building. Hitherto it has been a serious problem, unsolved so far as I am aware, to make the successive stories of a building sufficiently accessible to be available for use by any considerable number of 15 patrons. This is especially true of parking garages, located in the center of the city, where a large number of cars arrive close to a certain hour, or desire to depart at about the same time, and are impatient of 20 delay, as before and after business hours, or the theater. Partly for this reason garages have often been limited to two stories in height, notwithstanding the high cost of 25 real estate, in the section where they are located, and where other buildings are 30 higher. The objects of the present invention are attained by providing a re-curved inclined way, returning upon itself from floor to floor, so that at each floor there is a 35 portal which autos bound for a higher floor may pass without danger to or delay by any car on that floor, and where there is such a unification of the diverse grades of the inclined curve and of the level floor that 40 any car may conveniently issue from or enter the incline at any floor. The grade as a whole is such that cars can proceed up under their own power. The downward way, which may be separate from the upward way, and may be surrounded by it, 45 may have a steeper grade. The way may have the general aspect of a vertical helix, broken in continuity at each floor, however, by the interjection of a level section into its 50 course at the elevation of the floor and communicating therewith. Or, if the helix be unbroken, the level of the floor may be broken, for unification of floor with helix. Or, each of these methods may be employed 55 in part, for making connection between it and the floor. An advantage of the inven-

tion is that as the incline can be set in any part of the building, it permits the utilization of a city lot of irregular shape having a portion not well adapted for parking of 60 cars. When applied in a rectangular-shaped area, it can be put in the center thereof, furnishing walls against which berths for vehicles can be arranged. The invention may be applied in various ways, certain 65 illustrative embodiments of it being shown in the accompanying drawings. It is intended that the patent shall cover, by suitable expression in the appended claims, whatever features of patentable novelty ex- 70 ist in the invention disclosed.

In the accompanying drawings:

Figure 1 is a plan showing an upper floor of a garage with the apparatus of the invention in the midst of it;

Fig. 2 is an elevation, as if in vertical section through the building on the line 2-2 of Fig. 6, but with the building and ways somewhat modified in form as compared with the showing of Fig. 1 and some- 75 what diagrammatic;

Fig. 3 is a plan of a modification of the device illustrated in Figs. 1 and 2;

Fig. 4 is an elevation in section on the line 4-4 of Fig. 3, in diagram;

Fig. 5 is a diagram of another modification, in elevation, showing relations of grade of floor at a connection between the way and a floor; and

Fig. 6 is a plan showing by diagram the 85 device installed on an irregularly-shaped city lot.

In the drawings, and referring now particularly to Fig. 1, 10 indicates the walls and 11 indicates any one of the upper floors 95 of a building having street entrances to the first floor at 12, on the level of which entrances the sidewalk 13 is shown. In the center of this figure, one embodiment of the invention consisting of a pair of inclined 100 ways, 14, 15, is seen, each re-curved or turning back upon itself near to its point of beginning. As illustrated, these are circular, each occupying about two-thirds of a circle, and one of them surrounds the other. 105 From any given floor one incline runs down and the other up; while the space 16 surrounded by both of them is level. This produces an arrangement which, when the building as a whole is considered, bears some 110 relation to a helix; but the helix is subdivided into sections and is distorted at

each floor level. It has hitherto been proposed to use straight inclined planes for vehicles to run from the street to the second floor, and the reverse, but such inclines cannot be arranged in vertical succession, to go on to higher floors, without a wastefully extravagant use of floor space for vehicles to pass from the head of one incline to the foot of the next. Even then each incline would have to be relatively steep, and its entrance so located that cars approaching it from the floor must enter it with a sharp turn and so could not start on the rise under headway; and there would also be danger of collision between up and down going cars. I have discovered that by building re-curved inclines from floor to floor in vertical succession, the end of one delivering through a short straight zone to the beginning of the next, these serious objections can be obviated and the principles of the inclined plane and of self-propulsion can be applied conveniently, effectively, economically and safely. In buildings of ordinary height from floor to floor, for example, twelve feet, such an inclined way as may be wholly contained in a compass of 70x80 feet combines in itself the advantages of affording a rise from floor to floor of extraordinarily easy grade, of keeping the upward bound and downward bound cars clear of standing or parked cars; of debouching cars on each floor so that they are conveniently free either to go to a place on that floor or to go on up, and, if they go up, to start at speed on the incline to the next floor, practically straightaway if so designed, and in any event without a sharp turn at entrance; and of keeping oppositely bound cars practically free from the possibility of collision. The upgrade illustrated in Fig. 1, may, for example, be one foot in fourteen, and may complete the ascent from one floor to another in about two-thirds of a circle; and the remaining one-third of the circle may consist of open and level floor 11. This arrangement both reduces the width of space needed for the installation, by breaking out a segment of the circle, and leaves an ample level and straightaway floor space between successive inclines through which an upgoing car may maneuver at a comfortable speed either to go out upon the floor, or to start the next incline, or to avoid any car which is about to start oppositely. The straightaway aspect would be more obvious if the incline 14 were a somewhat larger fraction of a circle, equal, for example, to that of the incline 15. The downward going cars, passing over the way 15 within the upward way, may have a grade of about one foot in ten, with ample space for entrance and departure, and all cars may follow the general rule of keeping to the right, both in going around the floor and in taking either the up or the down in-

cline, so that cars have no sharp turns to make, and never meet, because they never go in opposite directions.

Figs. 2 and 1 together illustrate how a car, or any number of cars, entering on the street floor at 12 may proceed continuously and at speed to any floor above at any time, without any such delay as is encountered when an elevator is the means provided, or when cars are being moved about a floor, or are temporarily using the space in a floor over which the entering cars must pass. The building proprietor, moreover, saves the expense, care and attendance of the elevator, while the customer furnishes his own power and operates his own propulsion. At the same time, the inner wall 17 and the outer wall 18 of the ways afford a convenient place against which berths for standing cars may be arranged, either as indicated in the drawing, or otherwise. In Fig. 2, the flooring in space 16 at each level is omitted and the wall 17' is represented making a light well.

In some places, it may be preferred to use a single broad way, wide enough for cars going in opposite directions, as indicated by the illustration in Fig. 3. It may also be preferred to make the re-curved sections of incline continuous, instead of being intermingled with sections of horizontal floor, as indicated in Fig. 1. Both of these ideas are shown in Figs. 3 and 4, where, as seen in Fig. 4, the way 20 is a continuous helix, and, as seen in Fig. 3, it is planned that the same way may be used by cars going in opposite directions. In such a case, a line or a curb (not illustrated) might be arranged along the middle, dividing the way definitely into two parts. It is to be observed that in both the structure of Fig. 1 and in that of Fig. 3, there is a unification of grade of the way and the floor, so that the car issues from the way to the floor without any abrupt change of level. In Fig. 1, the course of the way becomes temporarily horizontal, as at 14', 15', and identical in level with the whole floor. In Figs. 3 and 4, the floor passing the portal of the way becomes sloping in conformity with the pitch of the incline passing the portal, from which slope a car makes the passage smoothly to or from the inclined way; and a suitable countervailing slope 22 is provided in the floor from the top of the slope 11'. In this arrangement, as in the others, cars may observe the rule of always keeping to the right, and of traveling around the floor only to the right. It is obvious that a car about to go in either direction on the incline 20 might approach perpendicularly to its portal on the surface 11', and turn in either direction without going over the rise 22.

Another way of applying the principle of bringing the plane or surface of the inclined way into practical unity with the plane or

surface of the floor is indicated in Fig. 5 which shows a different embodiment of the invention in diagram, and dimensions which represent the relative proportions stated except that the vertical scale is four times the horizontal: In this modification, it is assumed that the re-curved way sections are helical, with an outside diameter of about seventy feet, and that the way itself is twenty feet wide, thus allowing two ten foot halves for use respectively by up and by down going cars. In such a case, the outer edge may be assumed to rise twelve feet from floor to floor in about two hundred and twenty feet, and if the curve were a helix a rise of about 1.2 feet would occur in the twenty-two feet which may be assumed as the width of portal or opening in its wall, allowed for communication with each floor, being one-tenth of the entire circumference. The regularity of the helix may be varied so that one-half or 7.2 inches of this fractional rise assigned to the portal is distributed over the remaining nine-tenths of the circumference, where it would not be a burdensome addition, and the rise at the portal is thus reduced to 7.2 inches. Of this 7.2 inches, one-half may be absorbed in the central zone, *b*, of the portal by making 12 feet of the floor there slope at an incline agreeing with that of the outside line of the way past the portal, leaving 1.8 inches or rise to be overcome in the 5 feet at one side *a* and 1.8 inches at the other side *c* of the portal, making the floor of each part, *a* and *c*, horizontal at the level of the end of the portion *b* which is next to it. This horizontal bit of floor at the part *a* of the portal at the left of Fig. 5 would be 1.8 inches below the general floor level, and the part at *c*, would be 1.8 inches above the general floor level. Two feet from each jamb of the portal, for no car wheel would approach closer, there would be a difference of level of only about 1.1 inches, which is negligible. The slopes of 1.8 inches from main floor at the left to the depression *a*, and the same at the right up to the elevation *c* are also negligible and easily arranged at *a'* and *c'* respectively. As these variations of level are so slight as to be not objectionable to a highway vehicle, the general result is attained, of a portal of ample width affording free connection at reasonable speed between the inclined way and the floor, neither floor nor incline departing sensibly from continuity of grade, so that the full width of the portal may be used by cars moving in either direction.

Fig. 6 illustrates how the invention may be applied in a building of peculiar shape, which may be made to cover the whole of a lot of peculiar shape, it being only necessary to have a way leading from and to the entrance.

It will be observed that in all of the forms

illustrated the junctures or connections made with a floor by the approaching and the departing inclines of a series are grouped together. Cars passing up or down on that series therefore have no considerable travel on the floor, as in the case shown in Fig. 1, or at the level of the floor, as in Fig. 3, where they do not come upon the floor at all. This grouping together of junctures is so arranged as to allow a car either to continue on the series or to run to a berth on the floor; and those cars which are passing the floor to higher or lower stories do not interfere with the maximum freedom of use of berths on the floor at large, except of such few berths as may be located where the cars travel on the floor a short distance in passing between the junctions of the floor with the approaching and departing inclines of the up series, or of the down series.

In the appended claims, the word "floors" or "stories" is used in its ordinary signification of a definite principal horizontal section covering a considerable area, of a building, and large enough to hold a number of cars simultaneously. Although the kind of floor for which the invention will mainly be employed is for storing automobiles it is obvious that the invention may be used for handling automobiles between the ground and floors where they are wanted for other purposes as, for example, for receiving or shipping goods. The words "ground story" signify whatever floor of the building communicates with the ground, *i. e.*, has the automobile entrance and exit for the portion of the building to which the invention applies. From that floor upward the rise is approximately continuous, being interrupted only for the short spaces where a car is between the grouped-together junctures of the inclines with a floor. Likewise the curvature is approximately continuous. Preferably, and as illustrated, the curvature is on approximately the minimum radius on which automobiles can turn. With the story heights which are common for buildings, say twelve feet, the grade which results in the incline from story to story is suitable for automobiles. This arrangement of curvature leaves the main area of the floors outside of the area circumscribed by the course of cars ascending or descending, as spacious as may be desired, and reached by cars turning outward from the circuit into the storage space on any floor. This gives the required rise in a relatively short course without the grade being excessive in any part of it.

I claim as my invention:—

1. A device for the handling of automobiles between the ground and other stories of a building, comprising the combination, with a building having a plurality of stories other than the ground story, of a way com-

- prising a series of coöperating inclined ways arranged in succession from floor to floor, adapted in grade, course and surface for automobiles to traverse them, the several 5 ways of the series being arranged, in respect to each other and to the several floors, with the inclines of the succession approaching and leaving a floor having their connections with that floor grouped together.
- 10 2. A device for the handling of automobiles between the ground and other stories of a building, comprising the combination, with a building having a plurality of stories other than the ground story, of a way comprising a series of coöperating inclined ways, each adapted in grade, course and surface for automobiles to traverse it, extending between adjacent floors, and so curved in course as to have its termini at floors in locations which coöperate with termini of other ways of the series for passage of automobiles upon the series to or from a floor, or past that floor without traversing any considerable part of the floor.
- 15 3. A device for the handling of automobiles between the ground and other stories of a building, comprising the combination, with a building having a plurality of stories other than the ground story, of a way comprising a series of coöperating inclined ways, each adapted in grade, course and surface for automobiles to traverse it, extending between adjacent floors, and so curved in course as to reach each floor level near to, 20 and in direction running toward, the incline continuing the same series from that level.
- 25 4. A device for the handling of automobiles between the ground and other stories of a building, comprising the combination, with a building having a plurality of stories other than the ground story, of a way comprising a series of coöperating inclined ways, each adapted in grade, course and surface for automobiles to traverse it, extending between adjacent floors, and curved circularly 30 from floor to floor on a radius approximating the minimum on which automobiles can run.
- 35 5. A device for the handling of automobiles between the ground and other stories of a building, comprising the combination, with a building having a plurality of stories other than the ground story, of a way comprising a series of inclined ways arranged in vertical order within a section of the building, 40 said section being segmental in horizontal cross section and passing through a plurality of stories including the ground story, said ways being adapted in grade, course and surface to be traversed by automobiles, and being arranged around the arc side of the segment, and being connected with the successive floors at the chord side thereof.
- 45 6. A device for the handling of automobiles between the ground and other stories
- of a building comprising the combination, with a building having a plurality of stories other than the ground story, of a multiplicity of inclined ways coöperating together in two series on different radii of curvature 70 to handle the up and the down traffic from the various floors, the ways of one series being for the down bound cars with radius of curvature approximating the minimum around which automobiles can run, with the 75 grade from floor to floor which is consequent thereon, according to the height of the story; and the ways of the other series being for up bound cars and being arranged closely around those of the down series with the 80 grade from floor to floor which is consequent upon such location.
7. A device for the handling of automobiles between the ground and other stories of a building comprising the combination, 85 with a building having a plurality of stories other than the ground story, of a way joining the floors, adapted in grade, course and surface for automobiles to traverse it, curving repeatedly around a vertical axis, and arranged with connections to the various floors; the main floor-area served by the way being arranged outside of the area inclosed by the way, and said inclosed area being small relative to said outside area.
8. A device for the handling of automobiles between the ground and other stories of a building comprising the combination, with a building having a plurality of stories other than the ground story, of a way joining the floors, adapted in grade, course and surface for automobiles to traverse it, curving repeatedly around a vertical axis, and arranged with its total rise and total curvature each distributed approximately continuously along its extent from bottom to top of the said stories, with connections to the various floors; the area inclosed by the course being small relative to the area of floor served by it outside of its inclosed area.
9. A device for the handling of automobiles between the ground and other stories of a building, comprising the combination, with a building having a plurality of stories other than the ground story, of a way comprising a series of coöperating inclined ways arranged in succession from floor to floor, adapted in grade, course and surface for automobiles to traverse them, the several ways of the series being arranged, in respect to each other and to the several floors, with the inclines of the succession which approach and leave a floor having their connections with that floor grouped together; the said series of ways being arranged with the course of cars traveling through the series circumscribing a vertical section extending through said stories, and there being in said stories other space adapted to be traversed and occupied by automobiles outside of said

circumscribing car course; and a connection of the car course to said other space at each story.

10. A device for the handling of automobiles between the ground and other stories of a building comprising the combination, with a building having a plurality of stories other than the ground story, of a way joining the floors, adapted in grade, course and surface for automobiles to traverse it, curving repeatedly around a vertical axis and arranged with its total rise and total curvature each distributed approximately continuously along its extent from bottom to top, and with floor junctions on the outer side of said curvature, whereat cars on the said way can turn outward from the curve to leave the way; there being space on said floors connected to the way thereby and adapted to be traversed and occupied by automobiles.

11. A device for the handling of automobiles between the ground and other stories of a building, comprising the combination, with a building having a plurality of stories other than the ground story, of a way joining the floors, adapted in grade, course and surface for automobiles to traverse it, curving repeatedly around a vertical axis and arranged with its total rise distributed approximately continuously along its extent from bottom to top of the said stories, including an up grade past the levels of the various floors, with connections to the various floors in which the level of a floor that is being passed by the incline is interrupted by slightly inclined portions of the floor, in the locality where the way passes, facilitating passage of vehicles between floor and inclined way.

12. A device for the handling of automobiles between the ground and other stories of a building, comprising the combination, with a building having a plurality of stories

other than the ground story, of a way joining the floors, adapted in grade, course and surface for automobiles to traverse it, curving repeatedly around a vertical axis and arranged with its course occupying approximately three quadrants of circular measure between the adjacent floors, and one quadrant affording junction with each floor.

13. A device for the handling of automobiles between the ground and other stories of a building, comprising the combination, with a building having a plurality of stories other than the ground story, of a way comprising a series of coöperating inclined ways, each adapted in grade, course and surface for automobiles to traverse it, extending between adjacent floors, and so curved in course as to have its termini at floors in locations which coöperate with termini of other ways of the series for passage of automobiles upon the series to or from a floor, or, past that floor without traversing any considerable part of the floor, the direction of the incline varying in accordance with the direction of the curvature of the course.

14. A device for the handling of automobiles between the ground and other stories of a building comprising the combination, with a building having a plurality of stories other than the ground story, of a way joining the floors, adapted in grade, course and surface for automobiles to traverse it, curving repeatedly around a space with its strike varying approximately with the curvature of the course, and arranged with connections to the various floors; the main floor-area served by the way being arranged outside of the area inclosed by the way, and said inclosed area being small relative to said outside area.

Signed at Boston, Massachusetts, this 18th day of February, 1919.

CLINTON J. WARREN
